ADJUSTABLE VEHICLE TONGUE

Ummo F. Luebben, Omaha, Nebr.

Application August 31, 1951, Serial No. 244,569

2 Claims. (Cl. 280—462)

This invention relates to rotary balers of the type described in my previous patents issued to U. F. Luebben, both titled "Rotary Baler" Nos. 2,336,491, issued December 6, 1943, and 2,096,990, issued October 26, 1937.

It is an object of this invention to provide improvements upon the towing tongue now being used on this type of machinery.

Balers of this type trail to one side of the tractor when in operation and must trail more directly behind the tractor for highway travel. At present, to adjust the position of the baler with respect to the tractor, it is necessary for an operator to climb down from his tractor and pull out pins, then manually and laboriously swing the machine to the new position.

It is a primary object of this invention to provide an adjustable tongue for a rotary baler which will make it possible for the operator to make the above-described adjustment, without having to leave the seat of his tractor, by utilizing the power of the tractor without manual labor.

Another object of the invention is to provide a tongue which can be adjusted to more than two different positions so that the position of the baler can be adjusted for the widths of tractors of different sizes, thus eliminating the necessity of having the baler farther to the side than is necessary with a smaller tractor.

A further object is to have the baler position with regard to the tractor and windrow adjustable as described for proper central feeding of the machine.

Yet a further object is to provide a tongue assembly in which adjustable members are telescopically disposed one within another rather than being pivotally connected, thus providing greater strength.

Still another object of the invention is to provide an improved lock-pin assembly in which the use of chains is eliminated, the lock-pin being in an easily reachable position.

Still other objects are to provide an easily adjustable tongue assembly of greatly reduced weight, of reduced cost, of greatly simplified construction, of greater rigidity, and with greater adjustability.

Yet another object of the invention is to provide a device for the purpose described which is sturdy and durable in construction, reliable and efficient in operation, and relatively simple and inexpensive to manufacture, assemble and utilize.

In the drawings:

Figure 1 is a plan view of the adjustable tongue of this invention. A portion of a baling machine and various positions of the tongue are shown in dotted lines.

Figure 2 is a side elevation view of the adjustable tongue of this invention. A portion of a baling machine frame is shown in dotted lines.

Figure 3 is an enlarged side elevation view of the telescoping portion of the tongue of this invention, portions of the baling machine and one position of a locking pin being shown in dotted lines.

Figure 4 is an enlarged plan view of a portion of Figure 3.

Referring now to the drawings in detail and first to Figure 1, the adjustable tongue of this invention generally includes a normally horizontal elongated rigid longitudinal tongue portion 10, a normally horizontal telescoping portion 12 and a later described upwardly extending brace portion 13.

The rearward ends of the rigid portion 10 and the telescoping portion 12 are laterally spaced apart, and each

2

are pivotally disposed about bolts 20 for rotation in a horizontal plane.

Each of the bolts 20 are vertically disposed through apertures 22, the latter being disposed through the forwardly extending ends 24 of a hinge bracket 26.

The brackets 26 are preferably of strap metal and are welded or otherwise secured around the outside of a transversely disposed normally horizontal axle 28 of the baling machine 30.

10 As best seen in Figure 1 the baling machine 30 has a generally rectangular frame 32, the latter being disposed rearwardly from the axle 28, and at least two laterally spaced apart wheels 34, one of which latter is rotatably mounted on each end of the axle 28. One end 40 of the axle 28 extends outwardly from the side of the frame 32.

The bracket 26, upon which the rigid portion 10 is mounted, is disposed on the end 40 of the axle 28 and adjacent to the inner side of the wheel 34. The bracket 26, upon which the telescoping portion is mounted, is disposed adjacent to the center of the length of the axle 28.

As best seen from the side in Figure 2 the rigid portion 10 is rectangularly shaped. A pair of flat sheet metal brackets 50 are secured one each to the top and bottom surfaces of the extreme forward end of the rigid portion 10, and extend to one side thereof.

A tongue extension 52 is secured to the forward end of the longitudinal portion 10, having a portion of its bottom surface secured against the upper surface of the upper one of the brackets 50, by bolts 54. The extension 52 may be described as being rectangular as would be seen from the plan view, and has an upwardly extending offset portion 56 adjacent the center thereof and a forwardly extending horizontal portion 58.

The extension 52 has a vertically disposed aperture 35 60 through the forward end thereof to receive a bolt 62. The extension 52 is secured to a tractor drawbar 64 by the bolt 62.

As best seen in Figure 3 the telescoping portion 12 comprises a sleeve 70, the latter being rectangular in shape 40 as will be seen from the left hand end. An elongated rectangular shaped forward member 72 having a plurality of vertically disposed apertures 74 therethrough is telescopically disposed in the forward end of the sleeve 70. The member 72 has yet another vertically disposed aperture 76 45 at the front end thereof, which latter is pivotally disposed about a bolt 80, and between the laterally extending portions of the brackets 50.

The sleeve 70 is provided with a vertically disposed aperture 86 through both the upper and lower walls thereof.

50 A vertically extending hollow pipe 88 which latter is oblong in shape, as will be seen from the plan view, has its bottom end welded or otherwise secured to the upper surface of the member 70 in such a manner that the forward end of its hollow interior is an axial alignment with the aperture 86.

55 The invention further provides a locking pin 90, which latter is preferably made from a steel rod having one lower pointed end 92 and one upper end 94 bent into a circular shape leaving an aperture 96 therethrough so that it may be easily grasped by the operator and removed.

The pin is shown in full lines in the adjusting position where the lower pointed end 92 is disposed slightly to the rear of the aperture 86, and the body of the pin 90 is leaning against the forward portion of the interior surface of the pipe 88. The pin 90 is shown in dotted lines in the position that it assumes when it engages the apertures 86 and a selected one of the apertures 74 at such times as the telescoping action of the member 72 brings the aperture 74 into axial alignment with the aperture 86.

70 As is best seen in Figure 1, the tongue extension 52 at the forward end of the members 10 and 12 may be locked in any selected one of the positions 100, 102, 104 and 106.

The positions 100, 102 and 104 are for towing the machine 30 during the baling operation. The position 106 is for towing the machine 30 during road travel.

75 The baling machine 30 is provided with a forwardly and downwardly inclined pick-up conveyor of the number 110 which latter is trapezoidal in outline as seen from the plan view.

The rear or small end 112 of the conveyor is pivotally mounted on the forward portion of the baler frame 32 and directly above the rearward end of the telescoping member 12.

The lower forward or wide end 114 of the conveyor 110 is adapted to follow along the surface of the ground during baling operations, and to rest on the upper surface of the forward end of the member 12 when the tongue is in the position 106.

In Figure 2 the transporting position of the conveyor 110 is shown in full lines and the position for operation is shown in dotted lines.

The conveyor 110 is raised and lowered by a pair of upwardly and rearwardly inclined link rods 120, best seen in Figure 2, each of the rods 120 has its lower end pivotally attached to one side of the conveyor 110 and its upper end pivotally attached to an upwardly and forwardly extending leg 122 of a bellcrank 124.

Each of the bellcranks 124 is rigidly mounted at one end of a shaft 126, the latter being journaled at the upper forward end of the frame 32. One of the bellcranks 124 is provided with a downwardly and rearwardly extending leg 128 that is integral with the leg 122.

Each of a pair of rearwardly extending coiled springs 123 have one end secured to the leg 122 and the other to the top of the frame 32, and the springs 123 balance most of the weight of the forward end of the conveyors 110.

A vertically disposed link rod 130 has its upper end pivotally attached to the leg 128, and its lower end pivotally attached to the forward end 132 of a forwardly extending lever 133, the rearward end of which latter is mounted on a transversely disposed shaft 134.

The shaft 134 has its ends journaled in bearing brackets 136, which latter are welded or otherwise secured to the axle 28.

One of the brackets 136 is disposed adjacent to the baler frame 32, and the other is disposed adjacent to the inner side of the bracket 26 on the end 40 of the axle 28.

An elongated forwardly extending link rod 142 has its rearward end pivotally attached to the upper end of the lever 140 and its forward end pivotally attached near the bottom of a conveyor lift lever 144. The lever 144 has its lower end pivotally attached to a bracket 150 and extends upwardly therefrom.

The bracket 150 is secured near the forward end of the member 10 by bolts 152, and extends to one side thereof in the direction of the member 12. A lever quadrant 154 has each of its lower ends attached to the side of the member 10 on opposite sides of the bracket 150, the outline of the quadrant 154 being an arc having the bracket 150 as a center.

The quadrant 154 is provided with a plurality of teeth 156 cut into the upper arcuate surface thereof to engage the lower end of a pawl 158, the latter being in the form of an elongated rod having its upper end pivotally attached to a transversely disposed lever handle 160, the latter being pivotally mounted to the upper end of the lever 144.

As thus described, forward and rearward motions of the lift lever 144 will cause the conveyor 110 to be raised and lowered.

The invention is further provided with the before mentioned inclinedly disposed frame brace 13 best seen in Figures 2 and 3; the brace 13 being preferably of tubular pipe, having its lower end secured by a bolt 202 between a pair of rectangularly shaped brackets 204.

The brackets 204 are welded or otherwise secured to the sides of the member 70 and extend upwardly therefrom.

As best seen in Figure 3, the upper and rearward end of the brace 13 has a short portion bent to a horizontal position, and its most rearward end 208 flattened.

The flattened end 208 is pivotally attached to an upper forward member 210 of the frame 32 at a position directly above the rearward end of the member 70 by a bolt 212 for rotation therewith.

It will be understood that the pivot bolt 212 should be approximately directly above and aligned with the pivot bolt 20 of the telescoping member 70, but that certain misalignment is permissible because of the long length of the brace 13 and telescoping assembly 12 yet still affording approximately horizontal swinging.

From the foregoing description, it is thought to be obvious that an adjustable tongue constructed in accordance with my invention is particularly well adapted for use, by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

I claim:

- 20 1. A towing tongue assembly for a rotary baler comprising: an elongated longitudinal member pivotally attached at its rearward end to the axle of said baler at one end of said baler axle for pivotal movement in a horizontal plane; outer and inner telescoping members having adjustable combined effective length, said inner member having a plurality of longitudinally spaced apertures therethrough, said outer member having an aperture therethrough registerable with any selected one of said inner member apertures; an upwardly extending annular pin-holding member having its lower end attached to said outer member and opening onto its said aperture, said annular member being of large inner diameter at its lower end than said outer member aperture; a pin in said annular member supportable at times on said outer member adjacent said outer member aperture and disposable at other times through said outer member aperture and through a selected one of said inner member apertures, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 25 2. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 30 3. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 35 4. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 40 5. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 45 6. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 50 7. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 55 8. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 60 9. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
- 65 10. A towing tongue assembly for a rotary baler having a frame comprising: an elongated longitudinal member pivotally attached at its rearward end to the axle of said baler at one end of said baler axle for pivotal movement in a horizontal plane; two telescoping members having adjustable combined effective length, one of said telescoping members having a rearward end pivotally attached to said baler axle at a point adjacent the center of said axle, the other of said telescoping members having a forward end pivotally attached to said longitudinal member for pivotal movement in a horizontal plane; and means for attaching the forward end of said longitudinal member to a towing vehicle.
